UNITED STATES PATENT OFFICE.

JOHN J. MORSE, OF ST. LOUIS, MISSOURI.

REINFORCED BRAKE-SHOE.

1,112,376.

Specification of Letters Patent. Patented Sept. 29, 1914.

Original application filed August 19, 1912, Serial No. 715,707. Divided and this application filed July 21, 1913. Serial No. 780,130.

To all whom it may concern:

Be it known that I, JOHN J. MORSE, a citizen of the United States, residing at the city of St. Louis, State of Missouri, have invented 5 certain new and useful Improvements in Reinforced Brake-Shoes, of which the following is a specification.

This application is a division and continuation of one filed by me August 19, 1912, 10 serial No. 715,707 which resulted in Patent No. 1,095,019, dated April 28, 1914.

This invention relates to new and useful improvements in brake-shoes, and has for its object to provide a brake-shoe which is 15 composed of relatively hard and soft metals in order to obtain increased frictional and wearing qualities and at the same time to increase the strength and longevity of the brake-shoe.

20 In the accompanying drawings forming part of this specification, in which like numbers of reference denote like parts wherever they occur, Figure 1 is a transverse sectional view of a brake-shoe embodying the present 25 invention; Fig. 2 is a sectional view on the line 2—2, Fig. 1; Fig. 3 is a plan view of the pattern of the reinforcing element; Fig. 4 is a transverse sectional view of a brake-shoe having an alternate form of reinforcing element located therein; Fig. 5 is a sectional view on the line 5—5, Fig. 4; and Fig. 6 is a plan view of the pattern of the reinforcing element, which is used in the structure depicted in Figs. 4 and 5.

30 The brake-shoe 1 is preferably formed of cast-iron and is reinforced by a plate 2 of wrought, ductile, or other tough metal, which plate is preferably located near the back of the brake-shoe and is arcuated similarly to the back of the latter. The plate 2 bears a plurality of arms 3, some of which arms project from one side of said plate and others project from the opposite side of said plate, the arms 3 borne by one side of the 40 plate 2 being spaced apart and arranged in staggered relation with respect to the arms 3, which are borne by the other side of said plate and are, also, spaced apart, as best seen in the patterns of said plate depicted in Figs. 45 3 and 6. The arms 3 are bent so as to extend

diagonally through the body of the brake-shoe from opposite sides of the plate 2, so that the arms 3 borne by one side of said plate extend between the arms 3 borne by the other side of said plate, and, by this arrangement, not only anchor the plate 2 firmly in the cast-metal of the brake-shoe, but increase the frictional qualities of the wearing part of the brake-shoe. Said arms 55 3 may be of such length that same will extend substantially straight from the sides of the plate 2 diagonally through the body of the brake-shoe to a point near the wearing face of the latter, as depicted in Figs. 1 and 2, or, if desired, said arms may be relatively 60 long, in which case each arm 3 is bent at the point 4 intermediate the end of said arm and its point of juncture with the plate 2, so that the part extending between the bend 4 and the juncture with the plate 2 diverges 65 70 toward said plate, and the part extending from the bend 4 to the end of said arm diverges toward the wearing face of the brake-shoe, as depicted in Figs. 4 and 5. It should be understood that, if desired, the arms 3 75 may be still longer and provided with more bends 4 than shown in Figs. 4 and 5.

The brake-shoe may be provided with the usual key lug 5 having the usual opening 6 therein or with a plurality of such key lugs, 80 which lug or lugs may or may not be reinforced.

It will be evident that the wrought or ductile reinforcing plate not only increases the strength of the brake-shoe, but the presence 85 of parts of same in the wearing part of the brake-shoe enhances its braking qualities and thereby increases the longevity of the brake-shoe. By reason of using a plate having arms 3 as hereinabove described, the disposition and area of the wrought or ductile metal with relation to the cast metal in the wearing part of the brake-shoe change constantly as the braking face of the brake-shoe wears away in use, and in this way prevents 90 95 the braking face of the brake-shoe from wearing the tread of the wheel unevenly.

One great advantage in the construction of the reinforced brake-shoe of the present invention resides in the use of a back plate 100

having parts thereof bent so that same not only may extend into and form part of the wearing face of the brake-shoe, but may take the place of the inserts ordinarily used. In 5 this way the plate at or adjacent to the back of the brake-shoe is combined with the parts of same that may take the place of inserts in the wearing part of the brake-shoe, the result being the provision of a stronger 10 and more efficient brake-shoe.

I claim:

1. A brake-shoe having a body portion including a wearing member which extends toward the wearing face of the shoe in an 15 obliquely transverse direction, said wearing member being of different material from other material forming a part of the said body.

2. A brake-shoe having a body portion including a plurality of wearing members which are angularly disposed with respect to each other and which extend toward the wearing face of the shoe in obliquely transverse directions, said wearing members being of different material from other material forming a part of the said body.

3. A brake-shoe having a body portion composed of a plurality of materials one of which is a tough metal and the other of 30 which is a granular material, said body portion including members of the tough metal which are embedded in the granular material and which extend toward the wearing face of the shoe in transversely oblique directions.

4. In a brake-shoe, a plate of ductile metal located adjacent to the back thereof, said plate having extensions which are connected to the longitudinal sides of the plate and 40 project therfrom into the wearing part of the brake-shoe, the free end portions of the extensions terminating at points located adjacent to the longitudinal side of the plate opposite to the longitudinal side to which 45 the extensions are connected.

5. A reinforced brake-shoe composed of cast-metal and having a plate of ductile metal located adjacent to the back thereof and arms borne by said plate and projecting 50 transversely from the longitudinal sides of same into the wearing part of the brake-shoe, the arms borne by one side of said plate being arranged in staggered relation with respect to the arms borne by the other 55 side of the said plate and terminating at opposite sides of the plate.

6. A reinforced brake-shoe composed of cast-metal and having a plate of ductile metal located adjacent to the back thereof, 60 said plate bearing a plurality of arms which project transversely in spaced relation from the longitudinal sides of said plate into the wearing part of the brake-shoe and which

are of a length substantially equal to the width of the plate.

7. A reinforced brake-shoe composed of cast-metal having a plate of ductile metal located adjacent to the back thereof, said plate bearing a plurality of arms which project transversely in spaced relation from the sides of said plate into the wearing part of the brake-shoe, the arms borne by one side of said plate being arranged in staggered relation with respect to the arms borne by the other side of said plate and extending between same in the wearing part of the brake-shoe.

8. In a reinforced brake-shoe, a plate having transverse parts which extend from the opposite longitudinal sides thereof toward each other and toward the wearing face of the shoe and which are of a length substantially equal to the width of the plate.

9. In a reinforced brake-shoe, a reinforcement therefor consisting of intersecting parts transversely disposed with relation to the shoe and extending from opposite sides of the shoe toward the wearing face thereof and in opposite inclined directions and terminating at opposite sides of the shoe.

10. In a brake-shoe, a reinforcement therefor consisting of parts transversely disposed with relation to the shoe and extending from opposite sides of the shoe toward the wearing face thereof, said parts crossing one another.

11. In a brake-shoe, a reinforcement therefor consisting of parts transversely disposed with relation to the shoe and extending from opposite sides of the shoe toward the wearing face thereof, the outer ends of said parts terminating at the sides of the shoe opposite to the shoe side adjacent to which latter the inner ends of the parts are disposed.

12. In a brake-shoe, transverse intersecting reinforcements therein.

13. In a brake-shoe, reinforcements which extend toward the wearing face of the shoe 110 and intersect each other at points between the wearing face and the back of the shoe.

14. In a brake shoe, a plate having a series of arms on each side thereof, the arms on one side of the plate crossing the arms on the opposite side of the plate at points intermediate the ends of the arms.

15. In a brake shoe, sinuous reinforcements, portions of which intersect one another.

16. In a brake shoe, a plate and a sinuous extension connected to each side of the plate and being disposed beneath the plate and extending toward the wearing face of the brake shoe.

17. In a brake shoe, a plate and a sinuous

extension connected to each side of the plate, the extension on one side of the plate intersecting the extension on the other side of the plate.

18. In a brake shoe, a plate and a sinuous extension connected to each side of the plate, the extension on one side of the plate intersecting the extension on the other side of the

plate, at a multiplicity of points between the back and wearing face of the shoe. 10

In testimony whereof I hereunto affix my signature in the presence of two witnesses.

JOHN J. MORSE.
